UNITED STATES PATENT OFFICE.

FREDERICK J. DAVIS, OF WALTHAM, MASSACHUSETTS.

COAL-GAS CONDENSER.

SPECIFICATION forming part of Letters Patent No. 398,384, dated February 26, 1889.

Application filed July 1, 1887. Serial No. 243,103. (No model.)

To all whom it may concern:

Be it known that I, FREDERICK J. DAVIS, of Waltham, in the county of Middlesex and State of Massachusetts, a citizen of the United States, have invented a new and useful Improvement in Gas-Condensers, of which the following is a full, clear, and exact description, reference being had to the accompanying drawings, forming a part of this specification, in explaining its nature.

The invention relates to a condenser for the manufacture of coal-gas, which is adapted to be used in both the dry and wet processes of cleansing gas; and it comprises or embraces a vertical casing having sinuous passages therein joined at their top and opening at their bottom into the tar well or chamber. Any number of these cases may be used—generally three or four—and into the sinuous passages project from the inner walls of the case downward-extending flanges, which are arranged one above the other, and so as to cause the water introduced into the case from above, and where water is not employed the liquid freed from the gas by condensation, to leave the walls of the case and to drop from flange to flange, thereby acting mechanically to cleanse the gas, which of course is constantly passing up one sinuous passage and down the next in order.

The invention further relates to breakers extending into the tar-well between the exit of one case or section of the condenser and the entrance to the next one.

In the drawings, Figure 1 is a vertical central section of a gas-condenser having the features of my invention. Fig. 2 is a view in perspective thereof, a portion of the casing or wall being removed to show the interior construction. Fig. 3 is a view in perspective of the breakers.

In Fig. 1 the condenser is represented as having six separate sections or cases. Each section has two sinuous passages, *a*, which are connected with each other at the top by the curved passage *a'*, and which open at the bottom *a²* into the tar-well *B*, and one of which forms an uptake and the other a down-take. The gas enters the condenser through the pipe *C*, and passes down through a passage *a* to the tar-well *B*, thence through the

breakers *D*, which extend downward from the upper plate or covering of the tar-well very nearly to the bottom thereof, then upward through a sinuous vertical passage to 55 the top of the condenser, and then downward through the next passage in order into the tar-well, then through another group of breakers *D*, and upward and downward in the passages of the next case, as before. 60

Each section of the condenser has a vertical partition-plate, *E*, which extends downward into the tar-well. The tar-well is divided into chambers opening into the up-and-down passages of each section of the condenser, and the gas is thus obliged to take an onward course through the passages of the various cases or sections of the condenser. 65

The case *A*, which forms the passages *a*, is made in a number of sections adapted to be 70 placed one upon another, and they are formed by casting and have suitable joints whereby they are united.

The sinuous passage, which is quite wide and very thin, is formed by casting in the case *A* the horizontal concave sections *f* in each side of the case and diagonally opposite each other, and this forms in the passage the rounded sections *f'*, which are diagonally opposite each other and the inner edges of which 80 are upon the same perpendicular line. These edges, if merely rounded, do not provide for the dropping of water and the products of condensation of the gas, the water and liquid following the wall rather than forming drops 85 and dripping from the rounded surfaces. It is desirable that the water should leave the walls and drop from point to point through the passage, and for this reason I have formed—preferably upon each inner surface of the 90 rounded sections *f'*—the ledges *f²*, which are inclined from any desirable line or point of the surface downwardly, so as to make a form of surface from which the water or liquid is obliged to drop, and which acts to interrupt 95 the flow of water or liquid upon the inner surfaces of the walls of the case, and compels it to drop from projection to projection or ledge to ledge to the tar-well. The ledges also act to assist in the scouring or cleansing 100 of the gas by narrowing the passage in the condensers through which the gas is forced,

and also by offering sharp well-defined shoulders, against which the gas is broken and scrubbed in its course.

Generally in condensers of this kind water 5 in the form of spray is introduced into one section only, and I have represented in Fig. 1 the fifth section from the right-hand end as having the inlet-pipe *g*, through which water is introduced.

10 The breakers *D* comprise metal pins *d*, suspended by their tops from metal plates *d'*, and these metal plates are held in their proper places in the upper parts of the tar-well by the flanges *d''*, which extend upon the walls 15 of the well near the top, beneath the ends of the top plates of the well. (See Fig. 2.)

Having thus fully described my invention, I claim and desire to secure by Letters Patent of the United States—

1. A gas-condenser consisting of a series of 20 sections, the side walls of which are formed with concave portions *f*, diagonally opposite to each other, whereby a sinuous passage is formed, and the ledges *f'*, extending into said passages from the inner surfaces thereof, the 25 sections being connected together alternately at top and bottom, substantially as described.

2. The condenser having the walls or cases A, having sinuous passages *a*, connected with each other, as specified, the tar-well B, the 30 plates or partitions E, and the breakers D, placed alternately with said partitions, as and for the purposes specified.

FREDERICK J. DAVIS.
